UNITED STATES PATENT OFFICE.

DANIEL A. SHOEMAKER, OF WICHITA, KANSAS.

GRAIN SHOCKER.

Application filed June 9, 1924. Serial No. 718,827.

To all whom it may concern:

Be it known that I, DANIEL A. SHOEMAKER, a citizen of the United States, residing at Wichita, in the county of Sedgwick 5 and State of Kansas, have invented certain new and useful Improvements in Grain Shockers; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 This invention relates to a shocker for grain binders and harvesters, the primary object being to provide a shocker to receive bundles of grain, form them into shocks and deposit them upon the ground with the 20 heads upstanding.

25 The novel mechanism by which the desired result is accomplished will be apparent by reference to the following description in connection with the accompanying drawings, in which

Fig. 1 is a perspective view of a shocker constructed in accordance with my invention.

Fig. 2 is a plan view of the same.

30 Fig. 3 is a detailed perspective view of two parts of an intermittent clutch for setting the shocker into shock releasing operation.

35 Fig. 4 is a cross sectional view through the clutch showing the release device in elevation.

Fig. 5 is a side elevational view of the shocker in dumping position.

40 Fig. 6 is a similar view of the shocker in shock receiving position.

Fig. 7 is a detailed view of one of the shock forming elements.

Fig. 8 is a detailed perspective view of the clutch controlling stop and release, and

45 Fig. 9 is a fragmentary perspective view of one end of the crank shaft for operating the pitmen for swinging the bundle receiving members.

50 The shocker frame is shown as consisting of two end frame members 1 and 2. Each end frame member has a top rail 3 and a bottom rail 4, the top rail and bottom rail being connected at their ends by uprights 5 and 6 and they are braced intermediate

their ends by vertical braces 7. In actual 55 practice, the top rail 3, the bottom rail 4 and the vertical braces 5 and 6 can all be made of a single piece of strap iron.

The two frame members 1 and 2 are fastened together by cross bars 8 and 9, the 60 cross bars being additionally braced by a truss 10 having its ends fastened to the bar 9 and its intermediate portion to the bar 8. The bar 8 extends beyond the end frame 2, the end 11 being fastened to the binder 12 65 by a fastening device 13. The extended end 11 of the bar 8 has secured to it, one end of a brace 14 which is really the extended end of the bar 9 to assist in making the frame 70 rigid.

The sprocket 15 receiving motion from the binder mechanism drives a chain 16 which passes around a sprocket 17 on shaft 18 in bearing 19 carried by the bracket 20 of the shocker frame. The shaft 18 drives a gear 75 21 which meshes with a gear 22 on the shaft 23 mounted in bearings 24 and 25 carried by the shocker frame. On the end of the shaft 23 is a clutch member consisting of a star wheel 26 keyed to shaft 23 and having internal teeth 27 adapted to contact with the roller 28 on the projection 29 of the clutch dog 30. The clutch dog 30 is pivoted to a clutch disk 31 at 32 and the roller 28 on projection 29 is urged into the recess 33, 80 one end of which is connected to the dog and the other to the disk.

The dog has a foot 34 which projects beyond the periphery of the clutch members 90 and it may have pivotal movement because it is offset in the recess 35 in the clutch disk 31.

The clutch disk carries a beveled gear 36 and with the gear is loose on the shaft 23, 95 therefore the gear 36 will be rotated only when the roller 28 is moved into a recess between the teeth 27 which can be accomplished only when the foot 34 is free to move. Normally the dog is held out of the recess 100 by the stop and release device, best shown in Figs. 4 and 8. The stop and release device consists of a sleeve 37 pivoted on a spindle 38 on the frame and it has a stop arm 39 normally in the path of the foot 34. It also is provided with a crank stop arm 40, the purpose of which will be described herein- 105 after.

There is an arm 41 on the sleeve 37 to which is connected a pull rod 42 conveniently accessible for engagement by an operator on the harvester and binder so that at intervals the pull rod can be actuated to move the stop 39 out of engagement with the foot 34. When this is done the spring 33 will throw the roller projection 28 into the space between the teeth 27 and since the clutch member 26 is constantly rotating with the shaft 23, it will be apparent that the members 26 and 31 will be clutched together during one complete revolution of the shaft 23, at which time certain operations will take place as will be apparent after the construction of the invention is better understood. The pull rod 42 may be conveniently attached to the bundle carrier foot lever on the harvester and binder.

20 Mounted in bearings 43 and 44 on the top rails of the two end frame members 1 and 2 is a crank shaft 45. The crank shaft is provided with two arms 46 and 47 to which pitmen 48 and 49 are connected and integral with the arms 46 and 47 are offset crank arms 50 and 51 connected by the cross rod 52 to strengthen or brace the ends of the arms 50 and 51.

When the crank arms 50 and 51 are at greater radial distances from the bearings 43 and 44 than the arms 46 and 47 the throw of the cranks 50 and 51 will be greater than the throw of the cranks 46 and 47. Consequently the pitmen 53 and 54 will have greater amplitudes of movement than will the pitmen 48 and 49. The purpose of this will be understood by referring to Figs. 1, 2 and 7 from which it will be seen that the shock forming and supporting members comprise loops 55 and 56, each of which has a journal 57, one mounted in the bearing box 58 and the other in a box 59.

The loops are supported at their lower ends by brackets 60 and 61 which are pivoted to the boxes as indicated at 62 (Fig. 1), that is the upper end of each bracket 60 and 61 is pivoted to its box so that it can swing. Only one pivotal connection is shown in Fig. 1 but it is to be understood that the bracket 61 is pivoted to the box 59 in identically the same manner that bracket 60 is pivoted to box 58.

Each loop 55 and 56 carries lateral shock supporting fingers 63, the fingers of one loop projecting toward the other and each loop carries in addition, a spring finger 64 to absorb the shock of the bundles as they are dropped on to the shock receiving fingers 63. The pitmen 48 and 49 are fastened to the outer ones of the parallel bars 65 and 66 of the loops and the pitmen 53 and 54 are fastened to the inner ones of the parallel bars 65 and 66. That is the pitmen 48 and 49 are fastened respectfully to the bar 65 of the loops 55 and 56 and the pitmen 53 and 54

are fastened to the respective bars 66 of the loops 55 and 56. Consequently as the shaft 45 is rotated through the gears 36 and 67 (the latter being on the shaft 45 and meshing with gear 36) the loops or finger supporting members 55 and 56 will swing rearwardly due to the action of the pitmen 48 and 49, at the same time the pitmen 53 and 54 having a greater throw of amplitude of movement than the pitmen 48 and 49 will swing the loops about the axes of the pivots 59 to cause the fingers to spread apart as the shaft forming members move rearwardly, so it will be seen that the shaft forming members have two different movements imparted to them at the same time, one a downwardly and rearwardly swinging movement and the other a pivotal movement to cause the fingers 63 to spread apart. This is for the purpose of releasing the shock 85 and this peculiar movement is due to the fact that the stop 40 normally rests under the crank arm 46 but when a pull is imparted to the pull rod 42 to move the stop 39 out of engagement with the foot 34, the stop 40 is moved out of engagement with the crank 46 so that at the same time that the clutch is permitted to go into effect, the crank shaft 45 which has been previously held up by the supporting stop or arm 40 is released. The bundles of grain are fed into the cradle or shock forming device with the heads toward the rear and the butts rest upon the curved deflector plate 67 on rod 68 carried by the upper bar 3 of the end members 1 and 2. The butt supporting an up-ending plate 67 carries diverging angles 69 and 70 to tend to spread the butt ends of the shocks as they move to the ground, the shocks near the heads of the grain being compressed slightly by the upwardly and downwardly and then inwardly curved spring fingers 71 and 72 carried by the upper bars 3 of the ends 1 and 2 of the frame. The fingers 71 and 72 are a part 100 of the shock forming mechanism.

In actual practice I prefer to arrange the lower ends of the loops 55 and 56 so that they will swing about eight inches from the ground and about the same distance from the guides or angles 69 and 70 to allow room for spreading the butts of the shock. The lower ends of the shock will travel at about the speed the machine travels forward, so that it may readily be set up on the ground during the travel of the machine. The cranks on crank shaft 45 are set at such angles that the loops 55 and 56 and shock supporting fingers 63 which constitute swinging gates will have initial slow movement when opening, then a fast movement to full open position and then a relatively slow final closing movement so that fingers 63 will allow the butt ends of the shocks to contact with the ground and then move out 115 120 125 130

of the way of the shock at a rapid rate, this being necessary to prevent the shocks from being knocked down after they are set up as the machine travels over the ground.

5 Assuming that the shocker is moving from left to right the bundles will be fed into the shocker with the heads to the rear, butts resting upon the butt up-end plate 67. When a sufficient number of bundles 10 have been received in the shocker to make the shock, the operator will pull on the pull rod 42 to rock the sleeve 37 so that the stop 39 will move out of line with the foot 34. The spring 33 will then be effected in drawing 15 the dog 30 into contact with one of the teeth 27 and since the clutch member 26 is constantly rotating, it will be apparent that the clutch member 26 will cause the clutch member or disk 31 carrying the dog 30 to 20 rotate, imparting motion to the rock shaft 45 as previously described so as to dump the shock with the butt ends spread apart and the heads up-ended and inasmuch as the downward swing of the cradle arms or 25 fingers 63 will allow the butt ends to pass to the ground while the cradle arms or fingers 63 are spreading apart, it will be seen that the vertical shock must result.

The arms will support the shock long 30 enough to cause it to tilt to a vertical position and then the pitmen 53 and 54 will move the arms apart quick enough to allow the shock forming mechanism to get out of the way of the shock as the machine moves 35 forward, otherwise the shock will be knocked down.

From the foregoing, it will be seen that a shocker may be provided which will properly form the bundles as they come from 40 the harvester and binder into a shock and deposit it on the ground in an upright position.

The spring fingers not only absorb the impact of the bundles but they also tend to 45 tuck in the heads of the bundles as the shock is being made.

What I claim and desire to secure by Letters-Patent is:

1. A shocker attachment for harvesters 50 and binders comprising a frame, a shaft on the frame, means for constantly rotating the shaft when the shocker is in operation, a rock shaft on the frame, means for intermittently operating the rock shaft with the 55 constantly rotating shaft so that the rock shaft will partake of the motion of the constantly rotating shaft, pivoted bundle receiving members carried by the frame, means connecting the bundle receiving members with the rock shaft to impart an up and down swinging motion to the bundle receiving members, other means connecting the bundle receiving members to the rock shaft for imparting a laterally swinging motion to the bundle receiving members con-

current with the up and down motion of said members, and butt receiving means in front of said bundle receiving members.

2. A shocker attachment for harvesters and binders comprising a frame, a shaft 70 on the frame, means for rotating the shaft while the shocker is in operation, a rock shaft on the frame, means for intermittently connecting the constantly rotating shaft to the rock shaft so that the rock shaft will 75 partake of the motion of the constantly rotating shaft, pivoted bundle receiving members carried by the frame, means connecting the bundle receiving members to the rock shaft to impart an up and down 80 swinging movement to the bundle receiving members, other means connecting the bundle receiving members to the rock shaft for imparting a laterally swinging motion to the bundle receiving members concurrent with the up and down motion of said bundle receiving members, and butt receiving means in front of said bundle receiving members, said butt receiving means comprising a 85 downwardly and rearwardly directed plate. 90

3. A shocker attachment for harvesters and binders comprising a frame, bundle receiving members carried by the frame, said bundle receiving members having pivotal connection with the frame and being provided with fingers, the fingers of one bundle receiving member being directed toward those of the other bundle receiving member, a downwardly and rearwardly directed butt receiving plate carried by the frame, an intermittently operating rock shaft journaled in the frame, means for intermittently operating said rock shaft, a pitman connecting the bundle receiving members with the rock shaft to impart simultaneous up and down motion to said members, and pitman connecting the rock shaft with the bundle receiving members for imparting motion to said members and movement of the ends of said fingers to open 105 a gap between the members when the up and down movement occurs. 110

4. A shocker attachment for harvesters and binders comprising a frame, bundle receiving members having pivotal connection 115 with the frame and provided with fingers, the fingers of one member being directed toward those of the other member, a downwardly and rearwardly directed butt receiving plate carried by the frame, a rock shaft journaled in the frame, means for intermittently operating the rock shaft, a pitman connecting the bundle receiving members with the rock shaft to impart up and down movement to each member and whereby said members are moved in unison, pitman connecting the rock shaft with the bundle receiving members for imparting motion to the members whereby the ends of said fingers are separated to open a gap 120 125 130

between the members when the up and down movement occurs, and yielding fingers carried by said members to absorb the impact of the bundles received upon said members.

5 5. A shocker attachment for harvesters and binders, comprising a frame, bundle receiving members carried by the frame having pivotal connection with the frame and provided with fingers, the fingers of one member being directed toward those of the other member, a downwardly and rearwardly directed butt receiving plate carried by the frame, a rock shaft journaled in the frame, means for intermittently operating the rock shaft, a pitman connecting the bundle receiving members with the rock shaft to impart an up and down movement to each bundle receiving member and move the members in unison, pitmen connecting the rock shaft with the bundle receiving members for imparting motion to said members whereby the ends of their fingers are separated to open a gap between the bundle receiving members when the up and down movement occurs, yielding fingers carried by the bundle receiving members to absorb the impact of bundles received thereby, and yielding bundle guiding fingers carried by the frame for directing bundles downwardly from the bundle receiving members to form a shock.

20 6. A shocker attachment for harvesters and binders comprising a frame, a rock shaft on the frame having two sets of cranks, one set of cranks having a greater throw than the other set, means for intermittently operating the rock shaft, bundle receiving members carried by the frame having swinging movement in two directions, a pair of pitmen connected with one set of cranks on the rock shaft and to the bundle receiving members to impart simultaneous motion to the bundle receiving members in one direction when the rock shaft rotates, and a second pair of pitmen connected with the other set of cranks of the rock shaft and to the bundle receiving members to impart motion to the bundle receiving members in a different direction to that imparted by the first mentioned pitmen, and a butt guiding member in front of the bundle receiving members.

25 7. A shocker attachment for harvesters and binders, comprising a frame, a rock shaft on the frame having two sets of cranks, one set of cranks having a greater throw than the other set, means for intermittently operating the rock shaft, bundle receiving

members carried by the frame having swinging movement in two directions, a pair of pitmen connected with one set of rock shaft cranks and to the bundle receiving members to impart simultaneous motion to the bundle receiving members in one direction when the rock shaft rotates, a second pair of pitmen connected with the other set of rock shaft cranks and to the bundle receiving members to impart motion to the bundle receiving members in a direction different from that imparted by the first mentioned pitmen, and a butt guiding member in front of the bundle receiving members, the butt guiding member comprising a downwardly and rearwardly curved plate.

30 8. A shocker attachment for a combined harvester and binder comprising a frame, means for attaching the frame to the combined harvester and binder, a rock shaft, means for intermittently, operatively connecting the rock shaft with a movable part of the harvester and binder, the rock shaft having two sets of cranks, one set of cranks having a greater throw than the other set, a pair of looped members loosely connected with the frame, a pair of pitmen connected with one set of rock shaft cranks and with one arm of each set of looped members, a pair of pitmen connected with other set of rock shaft cranks and with the other arms of the looped members, lateral fingers on the looped members normally directed one toward the other, and butt guiding means in front of the looped members.

35 9. A shocker for harvesters and binders comprising a frame, a rock shaft on the frame, means for intermittently operating the rock shaft, the rock shaft having two sets of cranks, the throw of one set of cranks being greater than the throw of the other set of cranks, a pair of loosely mounted bundle receiving members carried by the rear of the frame, butt guiding means carried by the bundle receiving members, and two pairs of pitmen, one pitman of each pair being connected with the bundle receiving members and with the crank having the greater throw, one pitman of each pair being connected with the bundle receiving members and with a crank of the set having the lesser throw, whereby motion is imparted to each bundle receiving member in two directions to release the shock and spread the bundle receiving members apart.

In testimony whereof I affix my signature.

DANIEL A. SHOEMAKER.
